CLAIM

The ornamental design for a combined cup dispenser and straw holder, as shown and described.

DESCRIPTION

FIG. 1 is an oblique perspective view of a combined cup dispenser and straw holder embodying my new design;

FIG. 2 is a front elevation thereof;

FIG. 3 is a rear elevation thereof;

FIG. 4 is a side elevation thereof taken from the right of FIG. 2;

FIG. 5 is a side elevation thereof taken from the left of FIG. 2;

FIG. 6 is a top plan view thereof; and

FIG. 7 is a bottom plan view thereof.

FIG. 1.

FIG. 2.

FIG. 3.

FIG. 4.

FIG. 5.

FIG. 6.

FIG. 7.
